UNITED STATES PATENT OFFICE.

GEORGE T. PILLINGS, OF BALTIMORE, MARYLAND.

SAFETY STEAM-BOILER.

SPECIFICATION forming part of Letters Patent No. 269,458, dated December 19, 1882.

Application filed September 11, 1882. (No model.)

To all whom it may concern:

Be it known that I, GEORGE T. PILLINGS, of the city of Baltimore and State of Maryland, have invented certain Improvements in 5 Safety Steam-Boilers, of which the following is the specification.

This invention relates to a boiler having practically a vertical cylindrical shell of annular cross-section—that is to say, the shell is 10 composed of two wrought-iron sheets—an outer and an inner one—separated by rings, to which the said sheets are riveted to form a water and steam space. The boiler is open at its upper end, and the central cylindrical space 15 above that portion thereof which is used as a furnace is provided with a series of heaters consisting of tubes properly connected, which are in communication at the bottom with the water in the boiler and at their upper end filled 20 with steam.

In the further description of my invention which follows reference is made to the accompanying drawings, forming a part hereof, and in which—

25 Figures I and II are vertical sections of the improved boiler as seen from different points of view. Figs. III and IV are respectively a top view of the boiler proper and a section taken on the dotted line $x y$, Fig. I.

30 Similar letters of reference indicate similar parts in all the views.

A is the shell of the boiler, consisting of the outer and the inner wrought-iron sheets, respectively represented by a and b , and the 35 upper and lower separating-rings, c and d . The separating-rings are of the kind commonly used in vertical boilers to form a leg around the furnace; but the inner sheet, b , may be flanged out and riveted to the outer sheet, a , if 40 such construction is preferred. It will be seen that the inner sheet, b , extends to the top of the boiler, which is open at that point. Consequently the products of combustion from the 45 lower part of the boiler, which is used as a furnace, have free access, except where inter-

ferred with by the heaters hereinafter described, to the hood B, and thence to the smoke pipe or stack C.

D are wrought-iron tubes, secured at their lower ends to heaters E, which may be made 50 from cast or malleable iron or steel. The heaters E are varied in shape to suit the location in which they are placed; but they all correspond, in that they are in communication with the water-space in the shell and project through 55 a circulatory plate, F. The upper ends of the tubes D are screwed or otherwise secured into nozzles G, which are arranged in rows and secured together by means of bolts and caps. Each row of nozzles is connected to a steam- 60 drum, H, by means of pipes e , as is also the upper part of the shell.

One advantage of this construction of boilers is that the shell and the tubes all form 65 practically independent vessels, from which steam escapes to the drum without passing through a large body of water, as in ordinary boilers. The boiler is provided with a base and with grate-bars of ordinary description.

It will be understood that the annular shape 70 of the boiler-shell gives greater strength than can be obtained in any other form.

I do not limit myself to the construction of the boiler-shell of a cylindrical form, as other shapes may be used and the annular design 75 preserved.

I claim as my invention—

A practically upright boiler, which consists of a shell composed of two wrought-iron sheets connected at their ends by separating-rings 80 and rivets, inclosing a system of tubes connected at their lower end to the water-space of the boiler, separately or in groups, by means of suitable heaters, and at their upper end to a steam-drum at a point above the water-line, 85 substantially as specified.

GEORGE T. PILLINGS.
